CLAIM

The ornamental design for a monitor stand, as shown and described.

DESCRIPTION

FIG. 1 is a front, top and left side perspective view of a monitor stand showing my new design;

FIG. 2 is a rear, bottom and right side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof; and,

FIG. 9 is a partial enlarged view of FIG. 2 thereof.

The broken lines depict portions of the monitor stand that form no part of the claimed design.
